Primary Examiner — Cynthia R Underwood(74) *Attorney, Agent, or Firm* — iPA & iPM(57) **CLAIM**

The ornamental design for a case for a portable device, as shown and described.

DESCRIPTION

FIG. 1 is a perspective view of a case for a portable device showing my new design;

FIG. 2 is a top view thereof;

FIG. 3 is a front view thereof;

FIG. 4 is a left side view thereof;

FIG. 5 is a right side view thereof;

FIG. 6 is a bottom view thereof;

FIG. 7 is a back view thereof;

FIG. 8 is a perspective view from behind with a stand in an opened position;

FIG. 9 is a top view thereof;

FIG. 10 is a front view thereof;

FIG. 11 is a left side view thereof;

FIG. 12 is a right side view thereof;

FIG. 13 is a bottom view thereof;

FIG. 14 is a back view thereof;

FIG. 15 is a perspective view of the case affixed to a vertical surface; and,

FIG. 16 is a perspective view of the case resting on its open stand.

Features shown in broken lines in the drawings form no part of the claimed design.
